Attorneys

UNITED STATES PATENT OFFICE

HILTON E. DUNSETH, OF SAN ANTONIO, TEXAS, ASSIGNOR TO ANDERSON, CLAYTON & CO., OF HOUSTON, TEXAS, A JOINT STOCK ASSOCIATION OF TEXAS

COTTON CONDENSER

Application filed June 4, 1931. Serial No. 542,176.

The present invention relates to cotton condensers and, more especially, to improved means for removing dust, dirt, motes and other extraneous matter from the cotton.

5 An important feature of the invention is to provide means for preventing the air and dust entrained with the cotton fibers when it is introduced into the condenser from falling through the condenser screen drum and 10 mixing with the cotton after it has once been separated therefrom.

A further object is to provide a cylindrical screen drum with a series of plates which extend inwardly from the periphery of the 15 drum and are bent medially of their length to provide side portions which diverge toward the ends of the drum, so that the air and dust passing through the screen impinges 20 upon the plates, and is deflected towards the ends of the drum where it is withdrawn from the casing by the siphonic action of the air passing through the exhaust duct in the casing.

Another object consists in providing a 25 fender grid having a series of spaced downwardly inclined bars positioned adjacent the upper surface of the batforming drums for receiving the cotton lint as it falls from the cylindrical drum to separate the trash, motes, 30 and other foreign material from the cotton prior to its delivery to the batforming drums.

Further objects and advantages of the invention will become apparent from the following description, when taken in conjunction 35 with the accompanying claims.

Referring to the drawing, in which is shown a preferred embodiment of the invention,

40 Figure 1 is a vertical sectional view of a cotton condenser with the invention applied thereto.

Figure 2 is a perspective view of the upper portion of the condenser with parts in section.

Figure 3 is a detailed perspective view of one of the deflector plates.

Figure 4 is a detailed sectional view of the fender grid.

Referring to the drawing in which like numerals indicate corresponding parts in the several views, 10 designates a cotton condenser casing which is provided in one side thereof with an inlet duct 11 through which the blast of cotton laden air current from the ginning mechanism may be pneumatically or otherwise conducted to the casing. Within the casing is mounted a revoluble cylindrical drum 12 that is peripherally enclosed by the screen 13 and has its ends 14 (Fig. 2) open, so as to align with the spaced air and dust exhaust ducts 15 and 16 which extend from the top of the casing. The mesh of the screen 13 is sufficiently fine enough to prevent the passage of cotton fibers, leaf trash and other large foreign substances, but does permit the air and fine particles of dust to pass therethrough and escape to the outlet ducts 15 and 16, due to the siphonic action of the air passing through the outlet ducts 15 and 16. Each of the plates 17 is suitably secured to the inner periphery of the drum 12 and preferably bent intermediate its length as at 18 (Fig. 3), to provide the side portions 19 and 20, which extend to the ends of the drum adjacent the periphery thereof. The inner end of each plate 17 may be bent upwardly as at 21 to provide the trough 22 so that the air and dust passing through the screen 13 impinges against the sides 19 and 20 of the substantially plough-shaped plate 17 and is deflected to the ends of the drum where it is drawn through the exhaust ducts 15 and 16. Thus,

it will be seen that by reason of the withdrawal of the air and dust in this manner, the same is prevented from falling through the bottom of the drum and mixing with the cotton lint after the latter has passed over the drum 12 and conducted to the bottom of

- the casing. As the dust laden air discharged against and through the drum 12 travels at a much higher velocity than the drum itself, the plates 17 offer a resistance which deflects the dust and air to each end of the drum adjacent the periphery thereof so that it may be discharged through the exhaust ducts 15 and 16 in the manner as indicated by the arrows in Figures 1 and 2.
- 10 Positioned in the bottom of the casing 10 are a pair of batforming drums 23, which receive the cotton lint as it falls from the drum 12. In order to remove dust and leaf trash entrained with the cotton prior to its delivery to the batforming drums 23, there is positioned in the casing adjacent one of these drums a fender grid 24, which is secured to the casing by the strap 26. The grid 24 preferably comprises a series of downwardly inclined spaced bars 27, which is in the path of the cotton lint as it leaves the drum 12 so as to receive the same and acts to remove the dust and leaf trash from the cotton before it is delivered to the batforming drums 23. The space between the bars 27 allows the dust and trash to fall therethrough into a discharge chamber 28, having an opening 29 that is closed by a door 30 to permit the removal of the trash from the casing. A fender 31 secured to the inside of the casing adjacent the other of the batforming drums 23 guides the cotton that might pile up in the casing towards the space formed between the batforming drums. It will be seen that the cotton lint is directed to the batforming drums by the bars 27 and the fender 31 and after the lint has passed the drums 23, it is compressed and fed through a pair of oppositely rotating corrugated condenser rolls 32, which discharges the cotton into a suitable baling instrumentality not shown. Access may be had to the batforming drums and fender grid through the door 33 in the front of the casing.
- 45 It is to be understood that the form of invention herewith shown and described is merely illustrative of a preferred embodiment and that such changes as fall within the purview of one skilled in the art may be made without departing from the spirit of the invention and scope of the appended claims.
- I claim:
1. A condenser comprising a casing having an inlet duct for conducting a current of cotton laden air into the casing, a cylindrical screen drum revolubly mounted in said casing adjacent the inlet duct, said casing having an exhaust duct located above said drum, and deflector plates extending inwardly of the periphery of said drum, each of the deflector plates having a rear wall bent at its lower end to form a front wall of less width than the rear wall whereby to conduct the air and dust as it passes through the screen to

the ends of the drum adjacent the periphery thereof, to prevent the same from falling through the bottom of the drum, the siphonic action of the air passing through the exhaust duct acting to withdraw the air and dust from the drum. 70

2. A condenser comprising a casing having an inlet duct for conducting a current of cotton laden air into the casing, a cylindrical screen drum revolubly mounted in said casing adjacent the inlet duct, said casing having an exhaust duct located above said drum, and deflector plates extending inwardly of the periphery of said drum and terminating at their inner ends in upwardly projecting trough portions for conducting the air and dust as it passes through the screen to the sides of the drum adjacent the periphery thereof to prevent the same from falling through the bottom of the drum, the siphonic action of the air passing through the exhaust duct acting to withdraw the air and dust from the drum. 75 80 85

3. A condenser comprising a casing having an inlet duct for conducting a current of cotton laden air into the casing, a cylindrical screen drum revolubly mounted in said casing adjacent the inlet duct, said casing having a pair of spaced exhaust ducts located above said drum, and substantially plow-shaped deflector plates extending inwardly of the periphery of said drum, each of said plates having its medial portion extending in advance of its ends for conducting the air and dust as it passes through the screen to the ends of the drum adjacent the periphery thereof, to prevent the same from falling through the bottom of the drum, the siphonic action of the air passing through the exhaust ducts acting to withdraw the air and dust from the drum. 90 95 100 105

4. A condenser comprising a casing having an inlet duct for conducting a current of cotton laden air into the casing, a cylindrical screen drum revolubly mounted in said casing adjacent the inlet duct, said casing having an exhaust duct located above said drum, deflector plates extending inwardly of the periphery of said drum and co-extensive in length therewith, said plates being bent medially of their length to provide diverging side portions disposed in the rear of the medial portion for conducting the air and dust passing through the screen to the ends of the drum adjacent the periphery thereof, to prevent the air and dust mixing with the cotton lint after it has been separated therefrom, the siphonic action of the air passing through the exhaust duct acting to withdraw therewith the air and dust from the drum. 110 115 120 125

5. A condenser comprising a casing having an inlet duct for conducting a current of cotton laden air into the casing, a cylindrical screen drum revolubly mounted in said casing adjacent the inlet duct, said casing

120 125 130

having an exhaust duct located above said drum, deflector plates extending inwardly of the periphery of said drum and co-extensive in length therewith, said plates being bent 5 medially of their length to provide diverging side portions and terminating at their inner ends in troughs for conducting the air and dust passing through the screen to the ends of the drum adjacent the periphery 10 thereof to prevent the air and dust mixing with the cotton lint after it has been separated therefrom, the siphonic action of the air passing through the exhaust duct acting to withdraw therewith the air and dust from 15 the drum.

6. A condenser comprising a casing having an inlet duct for conducting a current of cotton ladened air into the casing a cylindrical screen drum revolubly mounted in said casing 20 adjacent the inlet duct, said casing having an exhaust duct located above said drum, deflector plates extending inwardly of the periphery of said drum for conducting the air and dust as it passes through the screen to 25 the ends of the drum adjacent the periphery thereof, a pair of batforming drums for receiving the cotton lint as it passes over said cylindrical drum and a fender grid extending transversely of the casing adjacent one of 30 said batforming drums for removing the trash and motes from the cotton prior to its delivery to the batforming drums, and a fender on the opposite side of the casing and directing the cotton lint toward the center 35 thereof.

7. A condenser comprising a casing having an inlet duct for conducting a current of cotton ladened air into the casing, a cylindrical screen drum revolubly mounted in said casing 40 adjacent the inlet duct, said casing having an exhaust duct located above said drum, deflector plates extending inwardly of the periphery of said drum for conducting the air and dust as it passes through the screen to the 45 ends of the drums adjacent the periphery thereof, whereby the siphonic action of the air passing through the exhaust duct causes the air and dust to be withdrawn from the drum, a pair of batforming drums for receiving 50 the cotton lint as it falls from said cylindrical drum, and a series of spaced downwardly inclined bars extending transversely of the casing adjacent the upper surface of one of said batforming drums for removing 55 the trash from the cotton prior to its delivery to the batforming drums.

8. In a cotton screen condenser drum, a deflector plate connected to the inner periphery of the drum, said plate being bent medial- 60 ly of its length to provide diverging side portions that extend to the opposite ends of the drum, the lower end of the plate being bent upwardly the whole length thereof to form a trough.

65 9. In a cotton screen condenser drum, a

deflector plate connected to the inner periphery of the drum, said plate being bent medial- 70 ly of its length to provide diverging side portions, the inner end of the plate being bent upwardly to form a trough.

10. In a cotton condenser drum, a substantially plow-shaped deflector plate secured to the inner periphery of the drum and co-extensive in length therewith, said plate having its lower end bent upwardly to form a trough. 75

In testimony whereof I have hereunto set my hand.
